UNITED STATES PATENT OFFICE.

JAMES McGINLEY, OF CHICAGO, ILLINOIS.

BOILER-CLEANER.

SPECIFICATION forming part of Letters Patent No. 286,724, dated October 16, 1883.

Application filed February 12, 1883. (No model.)

To all whom it may concern:

Be it known that I, JAMES McGINLEY, a citizen of the United States of America, residing at Chicago, in the county of Cook and State of Illinois, have invented a new and useful Improvement in Boiler-Cleaners, of which the following is a specification, to wit:

This invention relates to improvements in boiler-cleaners; and it consists in certain peculiarities of construction and arrangement, substantially as will be hereinafter more fully described, and set forth in the claim.

In order to enable others skilled in the art to which my invention appertains to make and use the same, I will now proceed to describe its construction and operation, referring to the accompanying drawings, in which—

Figure 1 is a plan view of a boiler with my improvement attached. Fig. 2 is a side elevation of the same, and Figs. 3 and 4 are detail views of the perforated pipes placed within the boiler.

A represents a steam-boiler of any of the ordinary and well-known forms, within which I arrange two pipes, *a a*, at the water-level, provided on each side with a series of perforations, *a'*, and connected by pipes *b b*, having globe-valves *b' b'*, with a cylindrical receptacle, *B*, located at one side of the boiler in any convenient position. In the bottom of the boiler I also arrange two perforated pipes, *c c*, one of which is connected by a pipe, *c'*, provided with a valve, *c'*, with the receptacle *B*, as shown in the drawings. The other pipe *c* is connected by a pipe, *d*, with a supply-pipe, *d'*, leading to the pump, and this latter pipe is provided with a globe-valve, *e*, by which the supply may be cut off at will, and between this valve and the pump it is also provided with a gate-valve, *e'*. The pipe *d* is connected to the receptacle *B* by a short section, *f*, which is provided with a globe-valve, *f'*, and also with a connection, *g*, having a valve, *g'*, leading to the waste-pipe, *h*, which connects the receptacle *B* with the sewer, and which latter pipe is provided, between the vessel *B* and the pipe *g*, with a valve, *h'*. The valves are all closed except those in the supply *d' d*, and water is pumped into the boiler until it reaches the proper height—level with the upper perforated pipes, *a a*. Steam is then raised and the valves in the pipes *c' c* and

b b are opened, when there will be a constant supply to the boiler through one of the pipes *c*, and a constant circulation through the other pipe *c*, the receptacle *B*, and the pipes *b b* and *a a*, which will draw off all sediment in the boiler and deposit it in the vessel *B*, where it may be drawn off at any time to the sewer by opening the valve *h'*. It will be readily understood that the shutting off of the pipe leading to the pump does not in any way interfere with the circulation through the other pipes and the receptacle *B*, and that any one of the pipes themselves may be blown off at any time without interfering with the action of the others—as, for instance, the closing of the valves *e* and *f'* and opening the valve *g'* will enable me to blow off one of the pipes *c* and the pipe *d* and *f* to the sewer without passing through the sediment-receptacle *B* or interfering with the circulation through the other pipes; or the other pipe *c* may be blown off without stopping the supply by simply shutting the valves *b' b'* and *f'* and opening the valve *h'* to the sewer. Again, the surface-pipes *a a* and their connections may be easily blown off by closing the valve *c'* and opening *h'*. The valves *f'* and *g'* always remain closed except when they are opened for special work, as the blowing off of one of the pipes, &c. It will be seen that this constant circulation of water through the lower pipes, *c c*, keeps the sediment in the bottom of the boiler stirred up and draws it off, while the upper ones, *a a*, draw off all that may collect upon the surface of the water. As seen by Fig. 4, the lower perforated pipes, *c c*, have their perforations arranged above and below and upon each side alternately, so that all dirt will be readily drawn off at any stage of the water, and the pipes not weakened by being perforated too closely. The pipes *a* and *c* have T-connection *x x* with the pipes *d* and *c'*, so that they can be disconnected, and the pipes *a* and *c* may be readily cleaned by the insertion of a rod or other means to prevent any crustation and to secure the free removal of sediment.

Having thus fully described my invention, what I claim as new, and desire to secure by Letters Patent, is—

In a boiler-cleaner, the combination of the shell *A*, provided with upper and lower perforated pipes, *a a c c*, with the pipes *b b*, hav-

ing valves b' b' , and pipe c' , having valve c' , all leading direct to the sediment-chamber B, and the pipe d , connected by a pipe, d' , having valve e and gate e' , with the pump, and also 5 connected with the vessel B by a short section, f , having a valve, f' , which latter is by a branch, g , having valve g' , connected around the receptacle B to the sewer or waste pipe h ,

all constructed and arranged to operate substantially as and for the purpose set forth. In testimony whereof I affix my signature in presence of two witnesses.

JAMES McGINLEY.
